UNITED STATES PATENT OFFICE.

FRED H. LINLEY, OF DULUTH, MINNESOTA.

MOTOR HOIST.

Application filed September 27, 1923. Serial No. 685,142.

To all whom it may concern:

Be it known that I, FRED H. LINLEY, a citizen of the United States, residing at Duluth, in the county of St. Louis and 5 State of Minnesota, have invented certain new and useful Improvements in Motor Hoists, of which the following is a specification.

This invention relates to a new and improved 10 motor hoist and more particularly to a hoist of this type driven by a motor both the field and armature of which revolve.

Hoists of this type are particularly 15 adapted for use in underground mining operations where the hoist is used to drag a scraper of ore for loading purposes. In such operations the scraper is normally dragged back to the ore pile by hand and 20 the drag cable should run freely during this return movement. By having both the field and armature revolve and having them revolve in opposite directions, the relative movement between the two members is increased 25 without increasing the movement of either relative to the hoist frame.

It is an object of the present invention to provide a new and improved hoist driven by a motor having a movable field and 30 movable armature.

It is a further object to provide a hoist of this character in which the field and armature are adapted to be gear connected so as to control their relative movement.

35 It is also an object to provide a hoist so connected in which the gear connection is controlled by centrifugal clutch.

It is an additional object to provide a hoist of this character in which the hoist 40 drum is carried by one of the moving elements.

Other and further objects will appear as the description proceeds.

I have illustrated a preferred embodiment 45 of my invention in the accompanying drawings, in which

Figure 1 is a longitudinal section taken on line 1—1 of Figure 2; and

50 Figure 2 is a cross section taken on line 2—2 of Figure 1.

The hoist comprises the frame 11 in which the hoist drum 12 is carried upon bearings 13 and 14. This drum 12 carries the field windings 15 of the motor. The shoulder 55 16 of the drum member carries the slip rings 17 and 18 to which the motor operat-

ing current is fed from wires 19 and 20. This current is transferred through brushes 21 and 22 to the armature commutator 23.

The armature 24 is carried upon the shaft 25 which rests in bearings 26 and 27 formed in the hoist drum member. The right hand end of the shaft 25 carries the gear 28. This gear 28 meshes with the gear 29 which gear fits loosely on the stub shaft 30. The gear 29 carries the centrifugal clutch members 31 adapted to coat with the clutch disk 32 which latter is directly connected to the shaft 30. The opposite end of the shaft 30 carries the small gear 33 which meshes 70 with the internal gear 34 formed upon the inner face of the hoist drum flange 35.

In the operation of the hoist, when it is desired to draw in or wind up the cable upon the hoist drum, the current is supplied to the motor. This causes the armature to revolve relative to the field. The gear 28 causes the gear 29 to revolve and when the proper speed is reached, the centrifugal clutch members 31 grip the clutch disk 32 thus rotating the small gear 33. This gear 33 meshes with the internal gear 34 formed in the hoist drum member and causes that member carrying the field to rotate in the direction opposite to the direction of rotation of the armature.

The relative movement, therefore, of the field and armature is made very high without causing the drum carrying the field to rotate at an excessive speed. This high 90 speed of relative movement permits the hoist to have comparatively high power and yet be of small size.

At the end of the hauling in movement, the current is shut off and the motor is stopped. When it is desired to haul out the cable to carry the scraper back to the ore pile, the cable is drawn out by dragging away the scraper thus causing the hoist drum to rotate in the reverse direction. 100 This rotation by means of the gear 34 causes the gear 33 and friction disk 32 to rotate. However, the clutch members 31 are at this time disconnected and consequently the armature is not rotated. The hoist drum itself thus rotates freely and the scraper may be drawn to the desired position without undue resistance by the hoist motor.

I have illustrated one preferred form of my construction and described one specific 110 application of it to a particular use. It is to be understood, however, that it is adapt-

ed for other uses and I contemplate such changes and modifications to adapt it to such uses as may come within the scope of the appended claims.

5 I claim:

1. In a motor hoist, a hoist frame, an armature and a field, both said members being movable relative to the hoist frame, gearing adapted to connect the armature and field to control their relative movement, and a speed controlled clutch adapted to bring said gearing into operation upon one of said members reaching a predetermined speed.
- 15 2. In a motor hoist, a hoist frame, an armature and a field, both said members being movable relative to the hoist frame, gearing adapted to connect the armature and field to control their relative movement, and a centrifugal clutch adapted to bring said gearing into operation upon one of said members reaching a predetermined speed.
- 25 3. In a motor hoist, a hoist frame, a field and an armature carried by said frame, a hoist drum carried by said field, both said field and armature being rotatable relative to each other and to the hoist frame, gears carried by the armature and hoist drum, and further gearing and a centrifugal clutch adapted to operatively connect the armature and hoist drums.
- 30 4. In a motor hoist, a hoist frame, a field and an armature carried by said frame, a hoist drum carried by said field, both said

field and armature being rotatable relative to each other and to the hoist frame, gears carried by the armature and hoist drum, and further gearing and a centrifugal clutch adapted to operatively connect the armature and hoist drums, the clutch being normally in its inoperative position.

5. In a motor hoist, a hoist frame, a field and an armature carried by said frame, a hoist drum carried by said field, both said field and armature being rotatable relative to each other and to the hoist frame, gears carried by the armature and hoist drum, and further gearing and a centrifugal clutch adapted to operatively connect the armature and hoist drums, the movable clutch members being driven by the armature gear.

6. In a motor hoist, a hoist frame, a field and an armature carried by said frame, a hoist drum carried by said field, both said field and armature being rotatable relative to each other and to the hoist frame, gears carried by the armature and hoist drum, and further gearing and a centrifugal clutch adapted to operatively connect the armature and hoist drum, the movable clutch members being driven by the armature gear, the clutch being normally in its inoperative position.

Signed at Duluth, Minnesota, this 17th day of September, 1923.

FRED H. LINLEY
